UNITED STATES PATENT OFFICE.

MICHAEL C. RYAN, OF OSWEGO, NEW YORK.

DESIGN FOR A CATCH-PLATE FOR BOX-FASTENERS.

SPECIFICATION forming part of Design No. 35,184, dated October 15, 1901.

Application filed September 7, 1901. Serial No. 74,701. Term of patent 14 years.

To all whom it may concern:

Be it known that I, MICHAEL C. RYAN, a citizen of the United States, residing at Oswego, in the county of Oswego and State of New York, have invented and produced a new and original Design for Catch-Plates for Box-Fasteners, of which the following is a specification, reference being had to the accompanying drawings, forming a part thereof.

As shown in the drawings, the leading or material feature of my design consists in the catch-plate having a general concavo-convex appearance when viewed in the side elevation. When viewed on top or bottom plan the body has the appearance of being enlarged at the ends, as shown in Fig. 1, the whole being stamped up from a single piece of metal.

a is the catch-plate, having a central portion b, convex when viewed from the top, slotted longitudinally, as shown at c, and terminating at its end in margins d, lying substantially in the same plane and having openings e. The sides of the blank from which the plate is stamped are substantially parallel, but when pressed into the shape desired take substantially the form shown at f in the drawings, the whole forming a unitary article of manufacture.

What I claim is—

The design for a catch-plate for box-fasteners substantially as herein described and shown.

In witness whereof I have hereunto set my hand on this 5th day of September, 1901.

MICHAEL C. RYAN.
